UNITED STATES PATENT OFFICE

1,991,628

CORK GRIP BUSH

Frank E. Rice, Detroit, Mich., assignor to American Tap Bush Company, Detroit, Mich., a corporation of Michigan

Application December 21, 1933, Serial No. 703,360

2 Claims. (Cl. 217—113)

This invention relates to a cork grip bush and more particularly to a tap bush for beer barrels or the like, provided with means for retaining a cork from accidental dislodgment outwardly of the bush.

5 An object of the present invention is to provide a tap bush with means for retaining a cork against accidental displacement outwardly of the bush.

10 Another object of the invention is to provide a tap bush with an undercut part for engagement by a cork to prevent dislodgment of the cork.

15 A further object of the invention is to provide a tap bush with cork retaining means to prevent accidental dislodgment of a cork inwardly or outwardly of the bush.

20 Generally speaking, the invention contemplates a tap bush having the rod receiving opening provided with means for positive engagement by a portion of the cork so as to secure the cork against accidental displacement with respect to the bush.

25 The above, other and further objects of the invention will be apparent from the following description, accompanying drawing, and appended claims.

30 The accompanying drawing illustrates an embodiment of the invention and the views thereof are as follows:

35 Figure 1 is a plan view of a tap bush constructed in accordance with the principles of the present invention.

Figure 2 is a vertical sectional view taken through the tap bush of Fig. 1, showing it in place in a barrel, and showing certain details of construction.

The drawing will now be explained.

The illustrated tap bush, as to outward appearances, is of the "Peerless" type which is well recognized in the trade.

40 A bush has a neck 1 having the usual overlying flanges 2 and 3 for engagement by lugs on a tap for interlocking the tap to the bush.

45 The neck 1 provides an opening for the pump rod, which opening is filled with a cork until such time as it is desired to tap the barrel.

The pump rod opening of the bush of the present invention is formed of different surface contours. The inner portion of the rod receiving opening, is, at 4, cylindrical or substantially so, and which is herein designated as the lower portion of the opening. Above the cylindrical portion a substantial length the opening is flared or diverges outwardly as at 5 where an inwardly directed flange 6 forms an annular inwardly extending shoulder. The flange 6 surrounds the opening 7 in the bush for receiving the pump rod and through which the cork 8 is inserted when it is desired to cork the bush. The flange 6, in

effect, provides an undercut shoulder 9 against which the outer or top face 10 of the cork abuts, when the cork is inserted in the bush.

5 The cork A is inserted through the opening defined by the flange 6 and forced into the bush opening until the upper face 10 of the cork is underneath the shoulder provided by said flange and the divergent portion 5 of the rod opening. The cork being expansive, will swell filling the divergent opening and such portion of the cork as extends below the inner face of the bush, will expand to interlock with the lower margin of the cylindrical portion 4 of the rod opening, whereby the cork is prevented from dislodgment, accidentally, inwardly or outwardly.

10 The inner end of the cork designated at 11, expands to prevent dislodgment outwardly, and also the upper end of the cork expands to engage against the undercut shoulder 9 to add to the preventative feature of outward displacement. The expansion of the upper end of the cork in the flared or divergent portion 5 of the opening, prevents accidental dislodgment of the cork inwardly of the bush, that is into the interior of the barrel.

15 For convenience, the upper surface or part of the tap bush is herein referred to as the "top side" and the lower portion or part or inner end, referred to herein as the "bottom side."

20 The invention has been described herein more or less precisely as to details, yet it is to be understood that the invention is not to be limited thereby, as changes may be made in the arrangement and proportion of parts, and equivalents may be substituted, without departing from the 25 spirit and scope of the invention.

The invention is claimed as follows:

2. A tap bush having a rod receiving opening through it, the part of said bush defining said opening being fashioned to provide the opening 40 as cylindrical inwardly from the bottom side of said bush and for a portion of the length of the opening and divergent towards the top side of the bush for substantially the balance of the length of the opening, said bush being provided with an inwardly directed flange forming a shoulder adjacent the top side of said bush.

2. A tap bush having a pump rod opening therethrough designed for the reception of a cork, the portion of the bush defining the opening 50 adjacent the top side of the bush being fashioned to provide an upwardly divergent opening to receive a substantial length of a cork, said bush having an inwardly directed flange adjacent its top side, the divergent opening being arranged terminating beneath said flange and having an axial length which is long as compared with the width of the inwardly directed flange.

FRANK E. RICE.
